DAMPER

Gustave Adolphus Peple, Jr., Richmond, Va.

Application April 18, 1942, Serial No. 439,492

2 Claims. (Cl. 98—40)

This invention relates to improvements in dampers and operating means therefor, the improvement being particularly applicable to air-conditioning systems for regulating the delivery of air from a duct to a room to be air-conditioned.

In air-conditioning systems it is the common practice to regulate the temperature and humidity of the air by a forced air circulation comprising a duct for withdrawing air from the room and a duct for delivering air to the room, the latter being connected with conditioning apparatus for modifying the temperature and humidity of the air to the extent desired. In order to obtain different conditions in different rooms connected to the same air-conditioning installation it is customary to provide dampers in the delivery duct from the conditioning apparatus so that the quantity of air delivered to the different compartments may be individually regulated as desired. Such regulation is also necessary to maintain the same conditions in different compartments which are subject to different rates of radiation, etc. Such dampers may be operated by hand or automatically operated through the agency of thermostats, etc.

The type of damper generally used for this purpose consists of adjustable louvres such as commonly used for hot air registers in domestic heating plants. Dampers of this type, however, are not satisfactory for air-conditioning apparatus, primarily for the reason that, except when fully open or substantially so, they produce drafts or eddy currents, with the result that the conditions prevailing in the locality adjacent the air delivery duct are different from conditions prevailing in the rest of the room. In a hot air heating system the eddy currents resulting from the faulty action of the adjustable louvre type of register are not so pronounced as in an air-conditioning system for the reason that the heated air in such systems is not under pressure from a circulating fan but flows only through natural convection and consequently produces little effect on the air currents in the room, regardless of the adjustment of the dampers. In pressure systems, however, the disturbance resulting from adjustable louvre dampers, particularly when the admitted air is colder than the air in the room, produces disagreeable effects.

My improved damper constituting the subject-matter of this application serves to regulate the quantity of air admitted to the room in a manner to substantially reduce at all positions of

damper adjustment the disturbance of the air throughout the room by the incoming air.

In the drawing I have illustrated a preferred embodiment of my invention, and in the said drawing:

Fig. 1 is a sectional elevation showing the damper installed in a duct for delivering air through a wall opening into a room;

Fig. 2 is a vertical sectional view on line 2—2 of Fig. 1 showing the damper in front elevation;

Fig. 3 is a detail sectional view on line 3—3 of Fig. 1 showing the damper-adjusting mechanism; and

Fig. 4 is a detail sectional view on line 4—4 of Fig. 3.

Referring to the drawing, 1 indicates the duct through which conditioned air is delivered from the air-conditioning apparatus to the room 2. The duct is shown as rectangular in cross section and at its discharge end is provided with an external collar 3 which is fitted into the wall opening. A grille 4 is mounted in the end of the duct in the usual manner with its flange concealing the juncture between the collar 3 and the wall.

Supported in the duct back of the grille is a casting 5 constituting the support for the damper and its operating mechanism. The damper blades 6 are hinged, respectively, at the top and bottom rear edges of the casting 5 and, as here shown, consist of flat sheet metal plates of rectangular shape and of a width greater than half the height of the duct opening, so that when the blades are adjusted to closed position, as shown in Fig. 1, they will present converging inclined faces to the air stream flowing through the duct into the room.

The damper blades are operated in unison so that the opening through the damper constituting the air passage will always be in the middle of the duct and the inclined converging faces of the dampers will serve to direct the air through the damper opening. Any suitable mechanism may be employed for simultaneously and equally adjusting the dampers. A simple, practical mechanism is illustrated in the drawing. The casting 5 is provided in the middle of its vertical wall on one side with a rearward extension 7 in which is formed a guide slot for a threaded block 9. The block 9 is held in the guide slot by means of a slotted cover 8, and pivoted to the inner face of the block where it projects through the slot in the cover 8 are operating levers 10 which are pivoted, respectively, to the dampers 6. The block 9 has a central bore parallel with the guide

slots and threaded with a coarse thread of quick pitch to receive an adjusting screw 11 whose forward end projects through the grille 4 and is provided with an operating knob 12. The adjusting screw 11 is supported in a journal 13 attached to the adjacent wall of the casting 5 and is held against longitudinal movement by a sleeve 14 surrounding the screw between the bearing 13 and the end of the guide 8.

By this arrangement the rotation of the knob 12 will adjust the dampers to any desired position between fully closed and fully open and maintain them in adjusted position.

The damper blades may be flat as shown or curved as disclosed in my co-pending application, Ser. No. 289,136, now Patent No. 2,281,615, dated May 5, 1942, of which this application is a continuation in part. The flat blades are cheaper to make and permit a duct opening substantially equal to the cross section of the duct, and for hand operation particularly, the flat dampers are practical and efficient.

While my improved damper is especially designed for hand operation, the construction may also be used with automatic control, for example, the damper-controlling mechanism illustrated in my co-pending application above referred to. It will also be understood that the details of construction may be variously modified within the spirit of my invention and the scope of the appended claims.

I claim:

1. A damper comprising a duct, two damper blades mounted in said duct for rotation respectively about axes adjacent opposite side walls of said duct, said damper blades being of a width considerably greater than the distance between

the axes of rotation of said damper blades whereby when said damper blades are turned inwardly to close the damper they will form a closure for said duct which is V-shaped in cross section, and means for simultaneously and equally turning said damper blades in opposite directions, said means comprising an adjusting screw mounted adjacent the end wall of said duct with its axis of rotation at right angles to the axes of said damper blades, a nut on said screw and mounted for longitudinal movement upon rotation of said screw, and links pivotally connecting said nut with said damper blades, respectively.

15. 2. A damper unit for air distribution ducts comprising a rigid frame of external shape and dimensions to fit snugly within the open end of a duct, said frame being open throughout substantially its entire cross section, damper vanes 20 hinged to two opposite side walls of said frame at points to the rear of the open end of said duct, said damper vanes being substantially greater in width than one-half the cross sectional dimension of said frame to thereby contact each other in fully closed position when substantially inclined to the transverse plane of said duct, and means for adjusting said vanes comprising a screw mounted for rotation in bearings attached to one end wall of said duct, the end of said screw projecting beyond the open end of said duct, a nut on said screw, a guide for said nut in the end wall of said frame and links connecting said nut to said vanes, respectively, whereby movement of said nut in said guide equally and oppositely turns said vanes on their respective hinges.
